APPARATUS FOR ASSEMBLING NAIL KNOBS

Filed Aug. 6, 1923

UNITED STATES PATENT OFFICE.

JOHN G. LOY, OF CAREY, OHIO, ASSIGNOR TO THE FEDERAL PORCELAIN COMPANY, OF CAREY, OHIO, A CORPORATION OF OHIO.

APPARATUS FOR ASSEMBLING NAIL KNOBS.

Application filed August 6, 1923. Serial No. 656,108.

To all whom it may concern:

Be it known that I, JOHN G. LOY, a citizen of the United States, residing at Carey, in the county of Wyandot and State of Ohio, have invented certain new and useful Improvements in Apparatus for Assembling Nail Knobs, of which the following is a specification, reference being had therein to the accompanying drawing.

10 My invention relates to an apparatus for assembling nail knobs of insulating material.

It is the object of my invention to provide a machine for assembling nail knobs by which the several parts will be accurately assembled with the minimum chance of breakage, at the maximum speed.

It is also my object to provide means of assembling small parts in their proper relationship to the remainder of the knobs, so that they will be automatically positioned and centered, thus eliminating the difficulty of accurately and rapidly handling such parts which has been heretofore experienced.

It is my further object to provide a machine which will enable a plurality of operators to be used, and which will so time the movements of such operators that a predetermined minimum production will always be maintained, and a tendency to lag on the part of any one operator will be eliminated.

It is also my object to provide a machine in which, if necessary, two or more of the operations may be performed by the same operator.

Referring to the drawings:

Figure 1 is a side elevation of my machine, with the parts in several stages of assembly.

Figure 2 is an enlarged side elevation of the assembled parts just prior to the hammer driving the nail through the metal washer, showing the supporting lagging and insulations in section.

Figure 3 is a similar view showing the nail driven home.

Figure 4 is a plan view of the lagging.

Referring to the drawings in detail:

1 is an endless chain passing over sprocket wheels 2 and 3, and actuated thereby. The

sprocket wheel 2 is mounted on the shaft 4, and the sprocket wheel 3 is mounted on the shaft 5. The sprocket wheel 2 has 55 associated with it, mounted on the same shaft 4, a ratchet 6, the teeth of which are engaged by the pawl 7, which is maintained in engagement with the ratchet wheel by the spring 8. This pawl is pivoted as at 60 9 to the end of the rod 10. This rod or actuating arm 10 is eccentrically pivoted as at 11 upon a crank wheel 12 turning in the direction of the arrow. This wheel is mounted upon an actuating shaft 13, 65 driven from any suitable source of power. Also mounted upon this crank wheel 12 is another actuating arm or link 14, known as the hammer arm. At the lower end of this hammer arm 14 is pivoted, as at 70 15, a hammer 16, which is directed by the guide 17.

Thus the movement of the hammer and the step by step movement of the chain are synchronized.

75 The chain carries a series of metal plates or lags 18, on which are mounted cups 19. The bottom of the cup is tapered as at 20 to an annular depression 21, in the center of which is an aperture 22.

80 The purpose of the annular depression 21 is to receive and position the small metal washer 23, which has an aperture 24 of smaller diameter than the diameter of the nail 25, so that the washer and one knob element will be retained in flat juxtaposition with their openings aligned and properly presented to the nailing means.

85 The porcelain portions of the knob are composed of an upper half 26, having a 90 lower corrugated face 27, and a central aperture to receive the nail, designated 28.

95 The lower porcelain member is designated 29, and has wire receiving depressions 30. It is also provided with a central passageway 31, for receiving the nail. This lower porcelain member is provided with an apron 32 surrounding an open base depression 33. This apron fits within the cup 19.

100 Operation. The operator stationed opposite station A drops the small metal washer 23 in the depression 21, which centers it. The washer settles into the recess of its own weight, being directed there-

to by the sloping walls 20. This steel washer is so small, and usually irregular in size, that heretofore it has been a great problem to handle it.

5 At station B the operator places the lower porcelain half 29 in the cup. At station C the operator places the upper half of the porcelain in position, and at station D the operator places the nail with the leather washer 34 thereon in the position indicated, with the point of the nail resting in the hole in the steel washer in the bottom of the cup, as in Figure 2.

10 At station E the assembly is brought beneath the hammer 16, which forces the nail downwardly through the washer, as in Figure 3. An anvil 35 supports the chain and plate at this point.

15 The completed assembly then passes over the sprocket wheel 2, and falls out of its own weight into the receiving hopper 36.

20 It will be understood that I desire to comprehend within my invention such modifications as may be fairly embraced within it, and as may be found necessary in adapting it to various conditions in the art in the course of the application of the invention.

25 Having thus fully described my invention, what I claim as new, and desire to secure by Letters Patent, is:

30 1. In a machine for assembling nail knobs, a conveying means, means thereon for locating an inserted metal washer and a knob part having a central opening so that said washer and knob part will be in flat juxtaposition with their openings alined, and means for later forcing a nail through said washer and said knob part.

35 2. In a machine for assembling nail knobs, a conveying means, means thereon for locating an inserted metal washer and a knob part having a central opening, so that said washer and knob part will be in flat juxtaposition with their openings alined, and means for forcing a nail through said washer and said knob part, said conveying means being arranged to permit the assembled parts to be ejected.

40 3. In a machine for assembling nail knobs, a travelling support, a series of lags thereon each adapted to receive and locate knob elements consisting of a washer and a lower member having a central opening so that said elements will be in flat juxtaposition with their openings alined, and a hammer operating in the path of the lags and means to actuate it to deliver blows upon a nail inserted in said knob elements.

45 4. In a machine for assembling nail knobs, endless chains constituting a travelling support, means of producing a step by step motion in said support, a series of lags on said support each adapted to receive, locate in flat juxtaposition with their openings alined

and discharge nail knob elements consisting of a washer and a lower member, and a hammer operating in the path of the lags and means to actuate it to deliver blows upon a nail inserted in said knob elements.

50 5. In a machine for assembling nail knobs, an endless conveyor, means for imparting step by step movement to said conveyor, means on said conveyor for locating a plurality of parts of a nail knob with respect to one another so that said parts will be in flat juxtaposition with their openings alined, and means synchronized with said step by step mechanism for driving a nail through the several parts.

55 6. In a machine for assembling nail knobs, an endless conveyor mounted on sprocket wheels, a plurality of spaced supporting members located on said conveyor, each of said members having a cup, a tapered bottom therein, an annular depression in the base of said bottom, having an aperture therethrough, said cup being adapted to locate a portion of the nail knob in position, and the cut-away portion in the bottom of the cup being adapted to receive and position a washer, and means adapted to drive a nail through the several parts of the knob.

60 7. In a machine for assembling nail knobs, an endless conveyor mounted on sprocket wheels, a plurality of spaced supporting members located on said conveyor, each of said members having a cup, a tapered bottom therein, an annular depression in the base of said bottom, having an aperture therethrough, said cup being adapted to locate a portion of the nail knob in position, and the cut-away portion in the bottom of the cup being adapted to receive and position a washer, means adapted to drive a nail through the several parts of the knob, means to impart step by step movement to said conveyor, and means to synchronize said step by step movement with the means to force the nail through the several parts.

65 8. In a machine for assembling nail knobs, a lag comprising a general body having a cup-like interior with inclined walls in the bottom portion thereof, whereby a washer placed in the cup will descend to the bottom and whereby a lower knob member may also be inserted in said lag.

70 9. In a machine for assembling nail knobs, a lag composed of a general body having a cup-like interior with inclined walls in the lower portion, a washer seat at the base of such inclination and an opening extending from said seat through the lag, whereby a washer placed in the cup will work down to the seat and whereby a lower knob member may be inserted in the lag, and a nail be projected through the lag into the washer to be later forced beyond the lag.

75 10. In a machine for assembling nail

knobs, a travelling support, a series of lags secured thereto, an anvil and a hammer in the path of said lags, one below and the other above such path, each lag having a cup-like interior adapted to receive nail knob parts and to permit the passage through it of a nail proper, the anvil being adapted to

support each lag when a blow is struck and the hammer adapted to strike each nail and drive it home.

In testimony whereof, I affix my signature.

JOHN G. LOY.
